END-TO-END COMMUNICATION SYSTEM
FOR RAILWAY TRAINS

Sylvester M. Viele, Swarthmore, Pa.

Application June 2, 1936, Serial No. 83,052

20 Claims. (Cl. 246—8)

My invention relates to end-to-end communication systems for railway trains and particularly to those systems which use high frequency electric currents located largely in the rails forming the tracks. In this type of system it is usual to employ coils carried at each end of the train and inductively coupled with the rails. One set of coils (one per rail) functions as a source of electromotive force in the rails and the coils at the other end of the train function as receiving coils. These functions of the coils may be reversed or two sets of coils, one as a transmitter and the other as a receiver, may be used at each end of the train. The electromotive force produced in the rail beneath the transmitter coils produces current flow therein to points remote therefrom in paths depending upon the admittance of the various paths. It is desirable to cause the greatest feasible proportion of the total current flow to pass the receiving coils in the rails beneath such coils. If the equipment is operating on a multiple track railroad it is also desirable that the current flow after passing beneath the receiving coils should be as widely diffused as possible so that the part of the total current flow appearing in an individual associated track which is not directly energized will be sufficiently small that it will not operate other communication equipment on adjoining tracks; otherwise there will be some interference between two equipments simultaneously functioning in close proximity even when on different tracks.

A low impedance of the total loop circuit is desirable in order to produce an operative condition with the limited electromotive forces available in such types of equipment.

In a railroad using a wayside signal system it is usual to segregate a track into signal sections, each section being electrically insulated from adjacent sections by the insertion in the track of insulating members commonly called block joints. These block joints form insulating elements for the wayside signal currents and materially reduce the efficiency of the track as a transmitting circuit for end-to-end communication systems on trains.

The installation of an end-to-end communication system using the rails as a part of the communication circuit therefor usually requires the installation of high frequency by-passes around these block joints. These by-passes are so designed that they will readily pass the high frequency currents of the communication system, but will not allow the passage of the rela-

tively low frequency wayside signal current in material amounts.

The present arrangement used is the shunting of signal block joints with high frequency bypasses, one type of which is the connection of the two rails of each of two adjoining sections by a resistance or capacity or both and then connecting the mid-point of each of these cross connections together.

With such an installation each track is electrically a continuous path for communication currents without cross connections between tracks except such as may incidentally occur by reason of track cross-overs. Leakage of communication current from the energized track is offered a relatively low impedance path in the associated parallel tracks of a multiple track railroad if such tracks have their signal block joints by-passed. The usefulness of the current leaking from the energized track at points lying between the transmitting and receiving points is practically lost. Experience has shown that in the case of a four-track railroad with one of the four tracks energized the current volume may be maximum in any one of the four tracks at distances from the transmitting end equivalent to a long train length. This division of the current in combination with the attenuation due to other causes may result in inadequate signal strength at the receiving point.

My invention has particular application to a railroad having two or more parallel tracks, one or more of which is electrically sectionalized at intervals by insulated block joints and the simple introduction of my invention into the existing wayside signal equipment is an important desideratum.

To sum up, the principal objects of my invention are: (1) to provide a means for lowering the electrical impedance of the total transmission circuit of an end-to-end communication system for trains using the rails as a part of the transmission circuit; (2) to provide a means of increasing the proportion of total current flow in the track beneath the receiver point; (3) to provide a means of dispersion of the current flow after it has passed beneath the receiver coils, associated on the same train with the transmitting coils; (4) to provide such means for easy connection into the wayside signal equipment in order that the latter may incidentally actuate the former; (5) to provide a simple and easy installation means of accomplishing the above objects which will progress with the train along the tracks.

Still other objects and advantages of my invention will become apparent from the following detailed description of certain preferred embodiments thereof, reference being had to the accompanying drawings.

Fig. I is a diagrammatic drawing showing my invention installed in a pair of tracks contemplating the use of wayside signalling apparatus and its associated block joints, and the use of end-to-end communication systems on only one of the tracks.

Fig. II is a diagrammatic drawing showing the installation of my invention in a four-track system, contemplating the presence of trains having end-to-end communication systems on only the two outside tracks.

Fig. III is a diagrammatic drawing showing my invention installed in a pair of tracks both of which contemplate the presence of trains thereon having end-to-end communication systems.

Fig. IV is a diagrammatic drawing showing a variation of the device of Fig. III in which the buses of Fig. I are added.

Before undertaking a detailed description of my invention as shown on the drawings it should be understood that railroad tracks as normally maintained are only partially insulated from earth and that if a track is energized with reference to earth or another point on the track, current leakages from and/or to the track takes place depending upon the conditions involved.

The degree of control of the amount and location of these leakages will largely determine the efficiency of use of the tracks as an electrical transmission path for communication purposes. With several tracks paralleling one another and each track segregated into partially insulated sections for wayside signal use it is possible to arrange these sections of multiple tracks into networks of such form as to produce circuits for transmission of communication currents in the tracks more efficiently than if no such arrangement was made.

In arranging the networks, use is made of buses interconnecting multiple tracks which are opened or closed by switches actuated by the wayside signal circuits, in accordance with the location of trains on the tracks. Use is made of signal block joint high frequency by-passes to produce electrically continuous tracks for the main transmission as well as to render available the characteristic impedance of the track earth circuit.

Where the leakage is abnormally high consequent of a very low characteristic impedance of the track earth circuit, it is desirable to reduce leakages as far as possible by the network arrangement.

In Fig. I there is shown a multiple track railroad consisting of two tracks 1 and 2. Track 1 is made up of sections electrically insulated from one another by signal block joints 3 as is common practice. At each block joint 3 there is provided a high frequency electric current by-pass 4 of the type referred to above, connecting to both rails of the track in each of the joined sections which is also common practice. The shown by-pass 4 has a resistance 8 at each end connected to the two rails of a track section, the resistances 8 being connected together at their midpoint as shown by wire 9. Each by-pass 4 is then bused to a corresponding point in track 2 by a bus circuit or connection 5 made up of wires 5a and 5b and the bus circuit 5 is opened

and closed by switch 6 which is operated by the relay 7. Each relay 7 is connected to the two rails of the track 1 in an insulated section so that the presence of a train in that section will operate its relay 7 to open the switch 6 only during the presence of a train in the section. Because the presence of a train in a section operates the switch 6 to disconnect the bus 5 associated with that section, the inoperative bus 5 does not shunt off communication current as the train passes the bus 5. If the bus 5 were not rendered inoperative as a bus while intermediate the ends of a passing train, it would shunt off the communication current and weaken the received signal communication current. Each relay is energized by a source of power 12 connected to each track section. The relay 7 may be replaced by the same relays which operate the wayside signal equipment now in use, as the wayside signal relays are similarly actuated by the presence of the train in the signal section. It is but a simple matter to adapt the signal relays to open the switches 6 at the same time the wayside signals are actuated by these signal relays, and close the switches 6 when the train leaves the signal sections appertaining to the switches 6. This easy connection into the wayside signal equipment is one of the advantages of my invention.

To explain the operation of this novel installation, it will be assumed that a train 10 is completely in a signal section of track 1 as shown. The train 10 is equipped with an end-to-end communication system of a type using inductive coupling with the rails on which the train 10 is operating and using the said rails as a part of the communication current transmission path.

With no train in the signal section, relay 7 holds switch 6 in a closed position and completes the interconnection of by-pass 4 to track 2. Relay 7 permits gravity to open switch 6 whenever a train 10 occupies the wayside signal section forward of the location of relay 7. Opening switch 6 opens the interconnection between tracks 1 and 2. The communication current network consists of a series of bussing connections between tracks 1 and 2, forward of, and rearward from, train 10; with the bussing connection between tracks 1 and 2 in the vicinity of the train 10 opened by switch 6. The switch 6 remains open until the train 10 has passed from the signal section with which the particular switch 6 is associated.

The communication current transmission may be considered as made up of several paths, among which are:

A path consisting of the energized track 1, made continuous by by-passes 4, to the first-closed bus point forward and rearward of the train position, with the bussing connection 5a through switch 6 and connection 5b, together with track 2 forming the completion of a full metallic loop circuit. This path may be traced as follows: start from a point in the rails 1 adjacent the transmitting inductor in train 10 and proceed to the rearward from the train 10, through the rails of track 1, through resistance 8, wire 9, resistance 8, rails 1, to the next resistance 8, wire 9, wires 5a and 5b of bussing connection 5, rails of track 2, wires 5b and 5a of bussing connection 5 ahead of train 10, wire 9, resistance 8 and back to rails 1 beneath the train 10 thus completing a metallic loop circuit.

A second path, consisting of track 1 to the bussed points forward and rearward of the train 10,

feeding into the entire characteristic impedance of the rail-earth circuit formed by two extended tracks 1 and 2 bused together at a plurality of points and the return loop formed by earth.

5 These two components of the total path function as one circuit producing a low impedance in the total circuit, a higher current concentration at the receiver point, a division of current after passing the receiver point and a dispersion of 10 the portion of current flowing into the characteristic impedance of the rail-earth circuit forward and rearward of the train position.

It is to be noted that there is no metallic shunting circuit formed by an interconnection between 15 tracks 1 and 2 intermediate of the train ends; also that a conductor such as a wire or cable might be substituted for track 2.

These conditions progress along the track with train movement along track 1.

20 In Fig. II my invention is installed in a four-track railroad system in which the outside tracks 21 and 24 are for freight use having end-to-end communication equipment of the above described type and the inside tracks 22 and 23 are for 25 passenger trains without such communication equipment.

This installation is but a more elaborate form of the one shown in Fig. I and operates in the same manner. Tracks 21 and 24 correspond to 30 track 1 of Fig. I, and tracks 22 and 23 to track 2 of Fig. I. It is apparent that the operation of relays 7 and switches 6 on tracks 21 and 24 is the same as in the device of Fig. I.

The communication current transmission may 35 be considered as made up of several paths, among which are: A path consisting of the energized track 24, made continuous by by-passes 4, to the first-closed bus point forward and rearward of the train position, with the wires 11a and 11b of 40 bussing connection 11 through switch 6, together with tracks 21, 22 and 23 forming the completion of a full metallic loop circuit.

A second path, consisting of track 24 to the 45 bused points forward and rearward of the train 10, feeding into the entire characteristic impedance of the rail-earth circuit formed by four extended tracks 21, 22, 23, and 24 bused together at a plurality of points and in parallel therewith a leakage section of these same tracks lying rearward and forward of the fully bused points with the return loop formed by earth. These two 50 components of the total path functioning as one circuit produce a low impedance in the total circuit, a higher current concentration at the receiver point, a division of current after passing the receiver point and a dispersion of the portion of current flowing into the characteristic impedance of the rail-earth circuit forward and rearward of the train position.

55 The path of the induced communication current will flow as follows: start from a point in the rails 24 adjacent the transmitting inductor in train 10, and proceed to the rearward from train 10, through resistance 8, wire 9, resistance 8, rails 60 24, resistance 8, wire 9, wires 11a and 11b of bussing connection 11, wires 9 and resistances 8 of rails 23, 22, and 21, now toward train 10 through rails 23, 22, and 21 made continuous by by-passes 4 composed of resistances 8 and wires 9, to wires 65 11a and 11b of bussing connection 11 ahead of train 10, through bussing connection 11 to wire 9 and resistance 8 of rails 24, through rails 24 under train 10 and back to starting point thus completing 70 a full metallic circuit. In further detail the 75 inside tracks 22 and 23 are permanently bused to-

gether and into the high frequency by-passes of tracks 21 and 24 by wires 11a and 11b forming connection 11 through switches 6 operated by relays 7. Buses 11 correspond to buses 5 of Fig. I.

With a train 10 occupying track 24, switch 6 is opened by relay 7 associated with track 24 and this track 24 is separated from tracks 21, 22 and 23 at points intermediate of the train ends and remains separated until the train 10 leaves the signal section, at which time relay 7 closes switch 6 10 and a new bussing point is formed at the rear of the train 10.

Assuming a train 10 on track 24 the return metallic loop for end-to-end communication current lying in track 24 is divided into three paths 15 formed by tracks 21, 22 and 23, and this path is in multiple with a return path formed by the entire characteristic impedance of the rail-earth circuit formed by four tracks multiplied together 20 extending forward and rearward of the train position.

These conditions progress with train movement along track 24. A similar description applies to track 21.

25 In Fig. III a modified form of my invention is shown installed in a two-track system, in which the presence of a train 10, equipped with end-to-end communication equipment on track 32, is shown. Operation of end-to-end communication on tracks 31 and 32 is contemplated.

30

This installation contemplates the case where both of the tracks 31 and 32 are divided into wayside signal sections insulated from one another by insulating block joints and further contemplates that the insulation from earth of one or both of 35 the tracks is less than normally occurring.

Between the rails at each end of each wayside signal section is connected a high frequency by-pass 14 similar to those previously described in Figs. I and II as by-passes 4 except that wire 19 40 (made up of wires 19a and 19b) of by-pass 14 is broken by a switch 16 which is operated by a relay 17 connected to the track adjacent the one with which the by-pass 14 is associated. Thus each by-pass 14 of track 31 is opened and closed 45 under the control of a relay 17 connected to track 32. A train 10 in a section of track 32 will by shunting power source 12 open by-pass 14 associated with the corresponding section of track 31. In this way, there is a reduction of the shunting 50 effect of track 31 over the train length which arises out of the abnormally high leakage from the track energized for end-to-end communication currents.

As train 10 progresses along the track 32 the 55 by-passes 14 between corresponding wayside signal sections of track 31 are progressively opened and again closed.

Fig. III contemplates the use of end-to-end communication on two tracks associated with 60 one another, which have an abnormally low leakage resistance to earth.

If, in any case, the main portion of the communication current remains in the rails of the energized track until after it passes beneath the 65 receiver coils, leakage in and beyond this point is very advantageous, but if such leakage takes place prior to reaching the receiver point, that is within the train length, such leakage reduces the strength of the received signal.

70

An actual connection from the energized track, intermediate of the train length, to a metallic path which would serve as a return path has a similar effect to leakage in this area and results in a reduced strength of received signal. Re- 75

moval of such connection or the provision of high impedance in them is highly desirable.

In this case, with each track made continuous by high frequency by-passes and one track energized, the other track acts as a metallic return path for such current as may leak onto it after leaving the energized track. This effect of the shunting action of the track associated with the energized track may be unimportant or very detrimental, in the latter case such effect may be reduced by opening the metallic continuity of the associated track.

The circuit of Fig. III is energized by apparatus on train 10 operating on track 32 made electrically continuous by high frequency by-passes 8, loop circuit 19 and switch 16 around the signal block joints 3. Switch 16 is operated by relay 17, the latter being associated with the associated track, in this case relay 17 of track 32 controlling the loop circuit 19 connected to the high frequency by-pass 8 in track 31 and vice versa. Relay 17 is controlled by the presence of a train in the wayside signal section with which relay 17 is associated.

With track 32 energized by equipment on train 10 the current flow is along track 32 into the characteristic impedance of the track earth circuit forward and rearward of the energized point with the return path in earth. The characteristic impedance is that of a single track; as there is no bus connection between tracks. A portion of the earth current leaks onto track 31 which portion of current is reduced by opening the metallic continuity of track 31 at points intermediate of the length of and behind train 10. By opening the by-pass 14 in associated track 31 the admittance of the metallic shunt path coextensive with the train length is reduced and a fuller utilization is made of the extremely low characteristic impedance of the rail-earth circuit composed of the multiplied track network formed forward and rearward of the train position. Obviously other tracks could be connected in to the system in the same manner.

Fig. IV contemplates the use of end-to-end communication on two tracks associated with one another, which have an abnormally low leakage resistance to earth. The arrangement of track network is such as to make the train occupied track continuous by the use of high frequency by-passes around the wayside signal block joints; to provide an opening in the metallic continuity of the track associated with the train occupied track in the section opposite and/or behind the train position; to use the characteristic impedance of the track earth circuit of all tracks forward of and behind the first point when both tracks are bused together to produce a lower leakage resistance to earth outside the train occupied section and to separate the energized track from other tracks—to preclude the direct metallic path interchange of communication current between tracks intermediate the train length.

This figure is similar to Fig. III except that an interconnection between tracks is provided, to function in accordance with the objects above delineated.

This diagram could be applied to tracks of Fig. II by making obvious changes in the connections. The circuit path of Fig. IV consists of an energized point on track 32 by apparatus carried by train 10. Track 32 is made electrically continuous, around wayside signal block joints 3 by high frequency by-passes 8, loop circuit 19 and switch

16 when the latter is in a closed position. Switch 16 is actuated by relay 17 operated by the wayside signal circuit of track 31. Forward of train 10 switches 16 are closed thus providing a continuous forward path along track 32 and 31.

In the rear of the train the first switch 16 of track 32 is open due to train presence and wayside signal circuit thus opening the by-pass 8 of track 31 but by-pass 8 of track 32 is closed through switch 16 of track 31. The next signal location further to the rear of the train is a duplicate of that existing forward of the train. This much of the circuit has provided electrical continuity of track 32 and of track 31 except for the single opening of track 31 intermediate or 15 behind train 10.

It is desired to bus the tracks together ahead of and to the rear of the train but not intermediate of the train. Use is made of part of loop circuit 19 with an additional connection and switch 18 actuated by relay 17 and a bus connection 15 which connects switch 18 associated with one track with switch 18 associated with the other track.

Current flowing forward along track 32 arriving at by-pass 8 flows to loop 19 at its point of attachment to the by-pass, along 19 to switches 16 and 18 operated by relay 17 of track 31, through switch 18 to bus connection 15 thence to switch 18 of track 32 and thence to the forward side of by-pass 8 of track 31. From loop 19 current also flows to switch 16 of track 31 thence through 19 to the forward side of by-pass 8 of track 32. The two tracks are now bused together forward of the train as well as made continuous.

Intermediate of the train length and/or to its rear, track 31 is opened; track 32 is continuous. The circuit at this latter location is identical with that previously described except that due to the presence of the train forward of this location 40 relay 17 is functional to open switches 16 and 18 associated with track 32. The open position of switch 16 opens the connection from one side to the other of by-pass 8 of track 31 which was formed by loop 19, closed through switch 16. 45 The closed position of switch 16 associated with track 31 together with loop 19 provides electrical continuity of track 32 past this point. The opening of either switch 18 (tracks 31 or 32) opens the bus connection 15 and separates the 50 two tracks at this location.

By these means a larger proportion of current flow originating at the transmission point is passed beneath the receiver point in the rails of the energized track. My invention therefore 55 considerably improves the operating efficiency of end-to-end communication systems and the simplicity and ease of installation, particularly in connection with existing wayside signal apparatus, is also an advance in the art.

While I have described the specific embodiments of my invention in detail above, it is obvious to one skilled in the art that a number of variations may be made without departing from the spirit of my invention as hereinafter claimed.

Having thus described my invention, I claim:

1. In a communication system, a railway track divided into signal sections by block joints of wayside signal equipment, high frequency by-passes around said block joints, a conductor in the vicinity of said track, a bus circuit connecting each said track section to said conductor, and means for automatically and temporarily opening each bus circuit as a train enters the section

associated therewith and closing said circuit as the train leaves said section.

2. In a communication system a pair of railway tracks, one of which is divided into signal sections by block joints of wayside signal equipment, high frequency by-passes around said block joints, a bus circuit connecting each said track section to the other track, and means for automatically and temporarily opening each bus circuit as a train enters the section associated therewith and closing said circuit as the train leaves said section.

3. In a communication system a plurality of railway tracks, buses connecting said tracks at spaced intervals, and means for automatically opening buses at any train occupied section of track and closing said buses behind said train as it progresses along the track whereby none of said buses is operative while intermediate the ends of a passing train.

4. An apparatus according to claim 1 characterized further by the fact that said means for automatically opening and closing said bus circuits are relays connected to the rails of said track sections.

5. In a communication system, a pair of railway tracks, each being divided into signal sections by block joints of the wayside signal equipment, by-passes around said joints, said by-passes having sufficiently low impedance to pass the high frequency electric current of an end-to-end communication system of trains and sufficiently high impedance to limit the passage of current of the wayside signal system to immaterial amounts, buses connecting the corresponding by-passes of each track, means for temporarily opening said by-passes of one of said tracks, and means for disconnecting each said bus from the other of said tracks when a train is present in the section associated therewith and opening at the same time the corresponding by-pass in the other track.

6. In a communication system, a plurality of railway tracks, each being divided into signal sections by block joints of wayside signal equipment, by-passes around said joints of such impedance that the high frequency current used in end-to-end communication systems on trains will flow but the lower frequency currents of the wayside equipment will not flow therethrough in material amounts, buses connecting the rails of corresponding sections of said tracks, and means for disconnecting each said bus from a train occupied section and opening at the same time one of said by-passes of each section of track corresponding to the occupied track section.

7. In a communication system, a railway track divided into signal sections by block joints of wayside signal equipment, high frequency by-passes around said block joints, a second railway track in the vicinity of said first track, a bus circuit connecting each said by-passes to said second track, a switch in each said bus circuit, and a relay for operating each said switch, said relay being connected to the rails of the signal section associated with the switch, whereby said switch is opened during the presence of a train in said section and closed when no train is present therein.

8. In a communication system, a pair of railway tracks divided into signal sections by block joints of wayside signal equipment, high frequency by-passes around said block joints, bus circuits connecting the corresponding sections of the tracks, normally closed switches in said bus

sections, relays for operating said switches to the open position by and during the presence of a train in the signal sections associated with the switches, switches in said by-passes, and relays for opening said last mentioned switches by and during the presence of a train in sections of the other track in the vicinity of the by-pass switch.

9. In a communication system, a plurality of railway tracks divided into signal sections by block joints of wayside signal equipment, high frequency by-passes around said block joints, bus circuits connecting corresponding by-passes, a normally closed switch in each by-pass for disconnecting the sections of one of said tracks from the bus circuit, normally closed switches in the by-passes of the other tracks, and a relay for opening each of said first mentioned switches by and during the presence of a train in the section associated therewith and at the same time opening and closing the second mentioned switches in the sections corresponding to sections associated with the first mentioned switches.

10. In a communication system, a plurality of railway tracks divided into signal sections by block joints of wayside signal equipment, high frequency electrical by-passes around each said block joints, bus circuits connecting corresponding by-passes to form a metallic network of tracks with multiple branches having distributed leakage to earth, and means for automatically disconnecting said bus circuits from a train occupied section of track thereby forming said train occupied area in said network of tracks into an area of high leakage resistance to earth in comparison to the surrounding network.

11. In a communication system, a plurality of railway tracks divided into signal sections by block joints of wayside signal equipment, high frequency electrical by-passes around each said block joints, bus circuits connecting corresponding by-passes to form a metallic network of interconnected tracks with multiple branches having distributed leakage to earth, and means for automatically disconnecting said bus circuits from train occupied sections so that at all times there is ahead of and behind the train position two networks of track connected together by a metallic conductor.

12. In a communication system, a plurality of railway tracks divided into signal sections by block joints of wayside signal equipment, high frequency electrical by-passes around each said block joints, and bus circuits connecting corresponding by-passes to form a metallic network of interconnected tracks with multiple branches having distributed leakage to earth ahead of and behind the train position, said track network being progressively formed into two networks connected together by a metallic conductor and this metallic conductor energized between the two networks for the electrical transmission of communication signals.

13. In a communication system, a plurality of railway tracks divided into signal sections by block joints of wayside signal equipment, high frequency electrical by-passes around each said block joints, bus circuits connecting corresponding by-passes to form a metallic network with multiple branches and means for breaking said network into two joined sections of network having distributed leakage to earth ahead of and behind the train position as the train progresses, said two sections being connected together by a metallic conductor for use as an integral part

of the electrical transmission circuit for end-to-end communication for trains.

14. In a communication system, a plurality of railway tracks divided into signal sections by block joints of wayside signal equipment, high frequency by-passes around each said block joints, bus circuits connecting corresponding by-passes to form a metallic network with multiple branches and means for breaking said network into two joined sections having distributed leakage to earth ahead of and behind the train position as the train progresses, said sections of network being connected together by a metallic conductor for use as an integral part of the electrical transmission circuit for end-to-end communication for trains and a full metallic return path in multiple with the track-earth return path between said two joined sections of said network.
15. The invention of claim 5 characterized further by the fact that a plurality of additional tracks are connected to said buses.

16. In a communication system, a pair of railway tracks separated into insulated sections, high frequency by-passes bridging said insulation, switches in said by-passes, relays connected to each said sections in each track for controlling the switches of by-passes of corresponding sections of the other track, and power source for operating said relays.

17. In a communication system, a pair of railway tracks separated into signal blocks, high frequency by-passes bridging the insulated joints, switches in said by-passes, relays controlling said switches, each said relay being connected to a different track from the one to which its associated switch is connected, whereby the presence of a train on one track opens the by-passes of the other track progressively, and a source of power for operating said relays.

18. In a communication system, a plurality of associated railway tracks separated into wayside

signal sections, means for connecting and disconnecting said track sections for electrically transmitted communication signals to form two connected networks having distributed leakage to earth; said connection between the two networks being the track occupied by a train progressively, and electrical means for transmitting communication signals through said train occupied section of track from one of said networks to the other and electrical means for receiving said communication signals.

19. In a communication system, a plurality of associated railway tracks separated into wayside signal sections, and means for connecting and disconnecting said wayside signal sections for electrically transmitted communication signals to form a loop circuit included in which are the signal section interconnecting means, the rails forming the energized track and the associated tracks, such loop circuit being at least coextensive with the location of the transmitting and receiver points.

20. In a communication system, a plurality of associated railway tracks separated into wayside signal sections, means for connecting and disconnecting said wayside signal sections for electrical transmitted communication signals to form a loop circuit consisting of the energized track, the associated tracks, and the signal section interconnecting means together with two connected networks having distributed leakage to earth, said connection between the two networks being the energized track; said loop circuit and said distributed leakage circuit being in parallel with one another and means for transmitting and receiving said communication signals through said circuits, both of said circuits progressing in steps concurrently with train movement along the track.

SYLVESTER M. VIELE. 40

DISCLAIMER

2,095,621.—*Sylvester M. Viele*, Swarthmore, Pa. END-TO-END COMMUNICATION SYSTEM FOR RAILWAY TRAINS. Patent dated October 12, 1937. Disclaimer filed June 22, 1940, by the inventor.

Hereby enters this disclaimer to claims 1 and 4 of said Letters Patent.
